UNITED STATES PATENT OFFICE.

EDWIN L. EMBREY, OF SPRINGFIELD, MISSOURI.

ADJUSTABLE WINDOW JACK.

Application filed December 20, 1927. Serial No. 241,359.

The present invention relates to improvements in scaffolds and has reference more particularly to an adjustable window jack.

One of the important objects of the present invention is to provide a window jack which can be readily and easily set up in position for use to permit a person to be properly seated outside of a window to facilitate cleaning of the window, and this in a safe manner.

A further object of the invention is to provide a window jack that is capable of adjustment in order to permit the use of the same with window frames of various widths, said window jack further including main sill engaging feet that are slidably adjusted on the spaced bars that extend outwardly through the window, auxiliary vertically adjustable feet being carried by said bars for engagement with the sub-sill to maintain the jack in a proper horizontal position when the seat board secured on the outer ends of the bars is occupied.

A further object is to provide an adjustable window jack of the above mentioned character which is simple in construction, inexpensive to manufacture, strong and durable, easy to manipulate, compact and convenient in its arrangement, thoroughly efficient and reliable in its operation, and otherwise well adapted to the purpose for which it is designed.

In the accompanying drawings, forming a part of this specification, and in which like numerals indicate like parts throughout the same:

Figure 1 is a top plan view of the adjustable window jack per se.

Figure 2 is a front edge elevation thereof.

Figure 3 is a sectional view taken substantially on the line 3—3 of Figure 1 showing the position of the jack with respect to a window.

Figure 4 is a bottom plan view of one of the slideable main sill engaging feet.

Figure 5 is a detail perspective view of one of the auxiliary vertically adjustable feet that engages the sub-sill, and

Figure 6 is a sectional view taken substantially on the line 6—6 of Figure 3.

In the drawings for the purpose of illustration is shown the preferred embodiment of my invention, the numeral 1 designates generally my improved window jack, the same comprising the elongated parallel spaced longitudinal bars 2 and 3 respec-

tively. A seat board 4 extends across the outer ends of the spaced bars and is secured to the upper edges thereof in any appropriate manner.

A window frame engaging bar 5 extends transversely across the upper edges of the inner ends of the longitudinal bars 2 and 3 and is secured thereto by the bolts 6, the ends of this cross bar extending beyond the sides of the longitudinal bars in the manner as clearly illustrated in Figure 1. Substantially rectangular shaped brackets that are formed from flat strips of metal and denoted by the numeral 7 in the drawing are secured on the upper edges of the inner ends of the longitudinal bars 2 and 3 and the inner face of the cross bar 5 is disposed against the inner side of the respective rectangular shaped brackets in a manner as clearly illustrated in Figure 3, the bolts 6 extending through the top and bottom sides of the bracket as also clearly shown in this particular figure of the drawings. The outer face of the cross bar 5 is spaced from the adjacent side of the respective bracket and the purpose thereof will be presently apparent. Additional rectangular shaped brackets 8 are carried by the respective ends of the cross bar 5 and the outer side face of the cross bar is also spaced from the outer side of the end brackets.

Extension bars 9 are slidably associated with the outer ends of the stationary cross bar 5 and these extension bars are slideable within the outer portions of the respective pairs of rectangular brackets 7 and 8. A pin 10 projects laterally from the intermediate portion of the outer side of each of the extension bars and engages the respective outer bracket 8 for limiting the outward sliding movement of said extension bars and thereby preventing the same from becoming disengaged with respect to the stationary main cross bar. The purpose of these extension bars is to provide a means whereby a window jack may be used in conjunction with window frames of various widths. These extension bars are slideable between the outer side face of the cross bar 5 and the adjacent side of the brackets.

Also forming a salient part of the present invention are the main sill engaging feet that are associated with the longitudinal bars 2 and 3. Each of these feet comprises a substantially inverted U-shaped yoke 11 that straddles each of the longitudinal bars.

Each of the arms of the yoke is formed with the laterally extending flanges 12 at the side edges of the lower free end portion thereof and the flanges are directed inwardly in the 5 manner as clearly shown in Figure 4 whereby to provide what may be termed a substantially rectangular shaped housing in the lower portion of each yoke for receiving therein a wooden block 13. A bolt 14 extends 10 transversely through the lower end portions of the arms of each yoke and through the central portion of the block for securing the same in position within the housing, a nut 15 being threaded on the threaded end of the 15 bolt in the manner as shown very clearly in Figure 6. The lower end portion of the block projects beyond the lower open end of the housing formed for the block while the upper edge of the block engages the 20 lower edge of a respective longitudinal bar in such a manner as to permit the free sliding movement of the feet along the bars. The lower end or bottom face of each block is preferably beveled in order to permit the 25 same to properly engage the main sill B as shown in Figure 3.

For the purpose of adjusting each of the 30 slideable feet so that the inner sides of the yoke member will engage the forward edge portion of the subsill C, I provide a chain 16 for each of the feet, one end of the chain being secured to an eye member 17 that is arranged on one side of the yoke 11, the intermediate portion of the chain being adapted 35 to extend through a suitable loop 18 formed at the outer lower corner of the respective rectangular shaped bracket 7. The free end of each chain is adapted to be secured to a hook 19 that is arranged on the 40 opposite side of the yoke and any one of the links of the free end portion of the chain may be engaged with the respective hook.

A retractile coil spring 20 is connected 45 at one end to the outer side portion of the block 13 as at 21 with reference more particularly to Figure 4, the other end of the spring being secured to the lower edge of the adjacent longitudinal bar outwardly of the yoke and this spring normally urges the 50 respective slideable hook outwardly along its bar.

The invention further comprehends the provision of subsill engaging feet and to this end, there is provided a pair of auxiliary feet such as are shown at 22 with reference 55 more particularly to Figure 5. Each of the auxiliary feet comprises a flat strip of metal that includes a vertical portion 23 and a laterally extending lower end portion 24. The vertical portion 23 is provided with a longitudinal slot 25 and a bolt 26 extends 60 transversely through the inner end portion of each longitudinal bar and through the

slot 25, a thumb nut 27 being threaded on the threaded end of each bolt and adapted 65 to engage the vertical portion 23 of each auxiliary foot for securing said foot in any vertical adjusted position. The laterally extending lower end 24 engages the subsill C in the manner as clearly shown in Figure 3. 70

The slot and bolt and nut connection provides means whereby each of the auxiliary feet may be properly adjusted in order to permit the window jack to rest in a horizontal position when in use and when the 75 cross bar 5 or its extension 9 engages the inner face of the window frame A, and the outer ends of the longitudinal bars are disposed beyond the outer side of the window, the jack will be properly supported so that 80 a person may occupy the seat board 4 and wash the windows on the outside in a safe manner.

A window jack of the above mentioned 85 character may be easily and readily adjusted and be properly positioned within the window and the sill engaging feet will cooperate with the window frame engaging cross bar to maintain the jack in a horizontal 90 position when the jack is in use. The simplicity of my improved jack enables the same to be constructed at a very low cost and by 95 reason of the extensible bars that are associated with the main cross bar, the jack may be used with windows of various widths. 95

While I have shown the preferred embodiment of my invention, it is to be understood that various changes in the size, shape and arrangement of parts may be resorted to, without departing from the spirit of the invention and the scope of the appended claim. 100

Having thus described my invention, what I claim as new is:

In a window jack of the class described, a pair of spaced longitudinal bars, the outer ends thereof adapted to extend outwardly of a window frame, a seat board arranged across the outer ends of the bars, an adjustable cross member secured on the inner ends of the bars and adapted to engage the inner face of the window frame, main sill engaging feet carried by the longitudinal bars, and means for holding said feet against the outer edge of the subsill of the window, said last mentioned means comprising a flexible element secured at one end to one side of each foot, a looped member at the inner end of each longitudinal bar through which the intermediate portion of the respective flexible member extends, the free end of the flexible member being adjustably secured to the other side of the respective foot. 115 120

In testimony whereof I affix my signature.

EDWIN L. EMBREY.
